Atty.

UNITED STATES PATENT OFFICE.

RICHARD FLEMING, OF LYNN, MASSACHUSETTS, ASSIGNOR TO THE
GENERAL ELECTRIC COMPANY, OF NEW YORK.

DESIGN FOR A CASING FOR LAMPS.

SPECIFICATION forming part of Design No. 29,301, dated September 6, 1898.

Application filed August 8, 1898. Serial No. 688,119. Term of patent 14 years.

To all whom it may concern:

Be it known that I, RICHARD FLEMING, a subject of the Queen of Great Britain, residing at Lynn, in the county of Essex, State of Massachusetts, have invented and produced a new and original Design for Lamp-Casings, (Case No. 906,) of which the following is a specification.

In the accompanying drawing, which illustrates my invention, is shown a perspective view of a lamp-casing.

The leading feature of the design is the configuration of the casing.

Referring by letter to the drawing, A represents a cylinder, and B a second cylinder, which is slightly smaller than cylinder A.

Surrounding the cylinders and located at a point between them is an ornamentation, band, or cornice C. On the upper end of cylinder A is a head or enlargement D, and near the bottom of the cylinder B is an ornamentation, band, or cornice E.

I claim—

The design for a casing for a lamp, substantially as shown and described. 25

In witness whereof I have hereunto set my hand this 4th day of August, 1898.

RICHARD FLEMING.

Witnesses:

A. F. MACDONALD,
DUGALD MCKILLOP.
